(57) **CLAIM**

The ornamental design for a frameless three-dimensional artwork display apparatus, as shown and described.

DESCRIPTION

FIG. 1 is a front perspective view of a frameless three-dimensional artwork display apparatus, in an assembled configuration. The three-dimensional artwork shown in dashed lines throughout these drawings provides environmental context only and is not claimed as part of the invention.

FIG. 2 is a front perspective view of the frameless three-dimensional artwork display apparatus of FIG. 1, in a disassembled configuration and without three-dimensional artwork.

FIGS. 3–8 are front perspective views of the frameless three-dimensional artwork display apparatus of FIG. 1, shown being assembled and then integrated into a three-dimensional artwork.

FIGS. 9–11 are front perspective views of the frameless three-dimensional artwork display apparatus of FIG. 1, shown being hung on a wall. The wall shown in dashed lines is drawn for environmental context only and is not claimed as part of the invention.

FIG. 12 is a front view of the frameless three-dimensional artwork display apparatus of FIG. 1.

FIG. 13 is a back view of the frameless three-dimensional artwork display apparatus of FIG. 1.

FIG. 14 is a right view of the frameless three-dimensional artwork display apparatus of FIG. 1.

FIG. 15 is a left view of the frameless three-dimensional artwork display apparatus of FIG. 1.

FIG. 16 is a top view of the frameless three-dimensional artwork display apparatus of FIG. 1; and,

FIG. 17 is a bottom view of the frameless three-dimensional artwork display apparatus of FIG. 1.
